Primary Examiner — Mark A Goodwin*(74) Attorney, Agent, or Firm* — Wood Herron & Evans LLP(57) **CLAIM**

The ornamental design for a rear part of a single drum roller, as shown and described.

DESCRIPTION

FIG. 1 is a front right perspective view of a rear part of a single drum roller showing my new design;

FIG. 2 is a front left perspective view thereof;

FIG. 3 is a front view thereof;

FIG. 4 is a right side view thereof;

FIG. 5 is a left side view thereof;

FIG. 6 is a rear view thereof;

FIG. 7 is a rear right perspective view thereof;

FIG. 8 is a rear left perspective view thereof;

FIG. 9 is a top view thereof; and,

FIG. 10 is a bottom view thereof.
